UNITED STATES PATENT OFFICE.

WALTER W. ADAMS, OF FORT WAYNE, INDIANA.

ALIGNING JIG FOR PISTON AND CONNECTING ROD ASSEMBLAGE.

Application filed May 22, 1922. Serial No. 562,614.

To all whom it may concern:

Be it known that I, WALTER W. ADAMS, a citizen of the United States of America, and resident of Fort Wayne, in the county 5 of Allen and State of Indiana, have invented certain new and useful Improvements in Aligning Jigs for Piston and Connecting Rod Assemblage, of which the following is a specification.

10 This invention relates to improvements in aligning jigs for piston and connecting rod assemblages, and the object thereof is the provision of a jig so constructed as to facilitate detection and the correction of 15 faulty alinement in the bearings of connecting rods and with their pistons, and also to provide a construction equally applicable to piston rods varying considerable in dimensions. A further object is to afford, in 20 connection with the jig, a straightening means for connecting rods.

The above objects are accomplished by the construction illustrated in the accompanying drawings in which:—

25 Figure 1 is a side elevation of a jig embodying the invention;

Fig. 2 is a front elevation projected from Fig. 1;

30 Fig. 3 is a plan view of the jig, a portion being broken away, including also a connecting rod positioned thereon; and

Fig. 4 is a detail view of the connecting rod rest positioned for connecting rods of large size, the view showing also one end 35 of the connecting rod mounted thereon.

The characters appearing in the description refer to parts shown in the drawings and designated thereon by corresponding characters.

40 The invention comprises a standard 1 having a hollow base 2, on the bottom of which is a lug 3 adapted to be held between the jaws of a vise (not shown) so the standard may thus be rigidly supported. The front 45 face 4 of the standard is dressed so as to present a true vertical plane, and the front face 5 of the base 2 is also dressed and presents a true vertical plane parallel with the face 4, there being an offset 6 in the standard between the two faces. The upper portion 50 of the standard has a vertical elongated slot 7 extending therethrough, and the base has at one side thereof a pair of integral jaws 8 and 9 spaced apart and horizontally disposed. The jaw 8 has upon its upper face a pair of ribs 10, and the jaw 9

has a screw 11 threaded therein that extends vertically in a plane midway between the ribs.

A rest 12, the inner end of which has a flat 60 foot 13, is adjustably positioned with its foot bearing against the face 5 of the base, there being a screw 14 extending horizontally through the base into the rest adapted when tightened to draw the rest firmly against the 65 face 5 of the base so as to be held rigidly in horizontal position. The rest is rectangular in cross section and has at each of its corners a rounded bead 15, 16, 17 and 18 respectively, and the sides 19 of the rest are wider 70 than the other two faces 20, and the beads are therefore spaced apart accordingly.

A gage member 21, the inner end of which has a flat foot 22, is adjustably positioned with its foot bearing against the face 4 of 75 the standard, there being a screw 23 extending horizontally through the slot 7 into the gage member, adapted when tightened to draw the member firmly against the face 4 of the standard so as to be held rigidly in 80 horizontal position. The gage member has three integral collars 24, 25 and 26 respectively which are spaced apart. The collars are precisely of the same diameter, and the collar 25 has on one side thereof a void 27 85 made therein for the purpose hereinafter set forth.

In utilizing the invention the standard is mounted in a vertical position in a vise by clamping the lug 3 between the jaws thereof, and the connecting rod 28 to be trued is placed with its bearing section 29 of its lower end set squarely upon the uppermost pair of beads of the rest. When connecting rods of the smaller sizes are applied, 90 the rest is adjusted to the position shown in Fig. 2 so that the uppermost pair of beads are sufficiently close as to accommodate the bearing of the connecting rod when placed thereon, and when the larger sizes of connecting rods are applied, the rest is adjusted to the position shown in Fig. 4 so that the uppermost pair of beads are spaced sufficiently apart to suit the bearing of the connecting rod. 100

105 The gage member is then adjusted vertically to a position on the standard so that the wrist pin 30 in the head 31 of the connecting rod may be brought into contact with the projecting faces of the collars on the 110 gage member by turning the connecting rod on the rest. When the head 31 of the con-

necting rod is too wide to be received between the collars 24 and 25, the gage member is turned so that its void, previously referred to, will afford clearance for the head 5 between the collars 24 and 26. While the bearing of the connecting rod is resting upon the beads the projecting portions of the wrist pin 30 should bear evenly against the corresponding collars when the connecting 10 rod is properly trued, and their failure to do so will be apparent, which will enable the operator to determine the extent the rod should be bent so that its wrist pin and bearing may be alined.

15 When a connecting rod is assembled with its piston (not shown), by placing its bearing upon the rest and sliding it toward the base until the piston bears against the face 4 of the standard, the parallelism of the 20 side of the piston with the adjacent face 4 of the standard is indicative of the alinement of the piston with the connecting rod.

Connecting rods, when found to be out of alinement, are inserted between the jaws 25 upon the ribs 10 and are bent by applying the screw 11. Or, the connecting rods may be held on the ribs by tightening the screw and then twisted by applying a wrench in the usual manner while thus held. These 30 operations are carried out until the connecting rods are found to be in alinement.

What I claim is:—

- 35 1. In an aligning jig for connecting rods, a standard; a rest extending from the standard for supporting connection with one bearing of a connecting rod, and a gauge member extending from the standard and having gauge collars of equal diameter and spaced apart in axial alinement with each 40 other and operable to bear respectively against the corresponding projecting ends of the wrist-pin in the opposite end of the connecting rod when said wrist-pin and the bearing in the other end of the connecting 45 rod are alined in a common plane.
2. An aligning jig for piston and connecting-rod assemblages, a standard having a flat gage face and a base, the front face of which is flat and parallel with the gage

face, there being an offset between said 50 faces; a rest having a flat foot that bears against the front face of the base, and having also a series of differently spaced beads 55 extending at right angles relative to said flat faces, and being adapted to be adjustably turned and held so that the beads may be positioned uppermost selectively in differently spaced pairs; and a gage member 60 adjustably positioned against the face of the standard and having three alined gage 65 collars spaced apart, the intervening collar having a clearance void therein.

3. In an aligning jig of the class described, a standard having a flat gage face; a rest having a flat foot that bears against 65 said flat face and having also a series of differently spaced beads extending at right angles to said face, and being adapted to be adjustably turned and held so that the beads may be positioned uppermost selectively in 70 differently spaced pairs; and a gage member having a flat foot that bears against said face and having alined gage collars spaced apart.

4. In an aligning jig of the class described, a gage means including a support 75 therefor, and a rest adapted to be adjustably positioned relative to the gage means and having a series of differently spaced beads and being adapted to be turned and so held so that the beads may be set in operative position selectively in differently spaced pairs.

5. In an aligning jig for piston and connecting rod assemblages, a rest including 85 support therefor, and a gage member adjustably supported in relation to the rest, and having three alined gage collars spaced apart, the intervening collar having a clearance void therein adapted to be brought 90 into operative position by adjustably turning the gage member.

In testimony whereof I affix my signature in presence of two witnesses.

WALTER W. ADAMS.
